S. LISKOW

HANGER BASKET AND BRACKET

Filed Aug. 1, 1921

FIG. 1.

FIG. 2.

FIG. 3.

FIG. 4.

FIG. 5.

S. LISKOW
INVENTOR
by John W. Strobel

ATTORNEY.

UNITED STATES PATENT OFFICE.

SIGMUND LISKOW, OF CINCINNATI, OHIO.

HANGER BASKET AND BRACKET.

Application filed August 1, 1921. Serial No. 488,981.

To all whom it may concern:

Be it known that I, SIGMUND LISKOW, a citizen of the United States, residing at the city of Cincinnati, in the county of Hamilton and State of Ohio, have invented certain new and useful Improvements in Hanger Baskets and Brackets, of which the following is a specification.

The object of my invention is to produce a new article of manufacture by forming a knock-down hanger or basket for use in connection with automobiles, motor trucks, articles of furniture and the like, which will be cheap, simple and highly efficient, which can readily be placed into form for use and quickly put out of the way when not used.

The various features of the invention and its advantages will readily become apparent from the following specification.

20 In the accompanying drawing forming a part of this specification.

Fig. 1, is a perspective view of my device or invention, in open or extended position.

Fig. 2 is a side view of the device with certain parts shown in various positions to illustrate construction,

Fig. 3 is an end view showing certain parts in both full and dotted lines to show varying positions of these parts.

30 Fig. 4 is a top plan view, parts being shown in various positions to illustrate the construction.

Fig. 5 is a view of the device in a knock-down form or position.

35 The device consists essentially of three bars 1, 2 and 3, the bar 1 usually being made stronger and heavier than the other two bars. Each of these bars has at each end an extension or arm, said arms being marked 4 and 5 and these arms and the bars are usually made integral. The bar 1 has attached thereto at the top of the extensions 4 and 5 a retaining bracket 6, which is rigidly attached to any article in connection with 45 which the device is to be used, by screws passing through the holes 7, 7, in said bracket.

The extensions 4 and 5 of the bars are pivotally connected together by the pins 8.

50 To the bar 2, I pivotally attach, by the pin 9, one end of an angularly shaped arm 10, which swings on the said pin 9, and at its other end 12 is bifurcated to engage with bar 1. To the central bar 1, I pivotally connect by pins 13, four arms 14, two of which 55 may be swung over onto the top of the arm 1

and the other two underneath said arm. Each of these four arms is provided with a locking recess 15 at its extremity. To each of the side bars 2, 3, I attach two arms 16 by pivot pins 17. Each arm 16 has a locking recess 18. These arms 16 may be moved into alignment with the bars 2 and 3, as shown in Fig. 5. The arms 14 and 16, when they are extended to meet each other, can 60 be locked together by means of the locking recesses 15 and 18.

When the device is in a knock-down form it appears as shown in Fig. 5, and through the brackets 6 it is held up against any object to which it is desired to attach the same. When the device is to be opened, the bars 1, 2 and 3 are swung into the position shown in Fig. 1; then the angular arm 10 is swung down and its bifurcated end 12 is made to 70 engage with the central bar 1; then the side arms 16 and bottom arms 14 are swung until they meet; and finally the locking recesses 15 and 18 are engaged. It can now be used for holding any article it is desired to 80 place therein; if it can be reached from the top, articles can be placed therein from above, if not, it can be filled through that side which does not have the angular arm 10; or it can be filled through any of the 85 spaces between the arms. It will be seen that the arms 14 can be swung into a position as shown in Fig. 4 if desired, (see Fig. 4), and that the arms 16 can be moved as shown in Fig. 2 to assist in locking or holding the contents of the basket. When it is desired to knock-down the device, the parts are swung again in position shown in Fig. 5, in which position the device occupies very little space and is out of the way. 95

I may form the device from flat strips of metal, or of wire, or other material. The arms and other parts may be of any form or shape, and pivoted together in any manner. If it is desired to remove the device 100 or to attach it to some other place, all that is necessary is to remove the screws from the brackets 6.

I do not wish to limit myself to the specific construction herein shown, but may 105 modify the same to some extent, but still fall within the scope of my invention.

What I claim as new and my invention and desire to secure by Letters Patent is:

1. A basket including central and side 110 longitudinally extending U-shaped members, each member consisting of a bar pro-

vided with end extensions, a pivot pin connecting all of the end extensions at one end of the basket together and another pivot pin connecting all of the end extensions at 5 the other end of the basket together, supporting arms pivotally connected to said bars and provided with latching elements, the latching element of each supporting arm being adapted to engage the latching 10 element of a complementary supporting arm to form transversely extending U-shaped parts to hold said U-shaped members in spaced position.

2. A basket as claimed in claim 1 including supporting brackets located at the ends 15 of the basket where said extensions are pivotally connected together.

3. A basket as claimed in claim 1 including an angular arm pivotally connected to 20 one of the substantially U-shaped side members and adapted to interlock with the central one of said substantially U-shaped members.

4. A basket including a plurality of substantially U-shaped members, pivots con-

necting the ends of said U-shaped members 25 together, each of said U-shaped members consisting of a bar provided with end extensions, supporting arms pivotally connected to each of the bars of the substantially U-shaped members near the ends of 30 the latter, each of said supporting arms being provided near its free end with a latching element and the latching element of each supporting arm being adapted to interlock with the latching element of a complementary 35 supporting arm for holding the substantially U-shaped members in spaced positions, and an angular arm pivotally connected to the bar of one of the substantially U-shaped members and provided with a 40 latching element adapted to interlock with the bar of another one of said substantially U-shaped members.

In testimony whereof, I affix my signature at Cincinnati, Ohio, this 16th day of 45 July, 1921.

SIGMUND LISKOW.
